Des. 746

Jonathan B. Brown, of Bristol, Conn.
Letters Patent No. 746, dated Dec. 11, 1858.

~~~~~  
The schedule referred to in these Letters Patent and making part of the same.  
~~~~~

To all whom it may concern,

Be it known, That I, Jonathan B. Brown of Bristol in the county of Hartford and State of Connecticut, have produced a new and original "design for a block frame", and I do hereby declare the following to be a full and exact description of the same, reference being had to the annexed drawings making part of this specification in which

Fig. 1, is a front or face view; and

Fig. 2, is a transverse section through the center.

I provide my frame in the form of an octagon (see fig 1.) In the center of this is the circle or disk for the clock face; surrounding this is a gilded ring (B fig. 1) outside of

2

Dec. 746 381

this I provide a hinge (c fig. 1); and also, a catch spring (d fig. 1); these two last parts are located upon the flat part or front of the frame. The several sides are angular, and each forms the part of an octagon. From the front surface of the frame I provide an oval slope or curve which terminates at the octagonal sides (see a, in the drawings); a, a, fig. 2, show the position of the octagon sides; a 2 in the same figure shows the back of the clock, which a, a, in the same figure defines the oval corner, which is the principal part of my production.

Having thus fully described my invention or production, I wish it understood that I do not claim an octagon form only as my design inasmuch as such form has before been used, but what I do claim as my production is the combination of the octagon form with the oval corner as distinguished from some other form.
